An electrical bushing assembly having an electrical conductor extending through a solid body member cast of insulating material, a rigid metallic mounting member or flange having a generally circular opening therein, a certain portion of said flange adjacent to the opening being embedded in said cast body member, and a cylindrical-shaped, thin, less rigid metallic member attached to said flange adjacent to the opening therein. The less rigid metallic member is completely embedded in the resin of the body member. The bushing assembly is mounted in sealed relationship to a casing enclosing electrical apparatus and fluid dielectric by welding the rigid mounting member or flange to the casing.

FIG. I.

FIG.2.

FIG. 3.

FIG.4.

CAST EPOXY BUSHING HAVING A WELDABLE FLANGE

BACKGROUND OF THE INVENTION

1. Field of the Invention

The invention relates in general to bushings for electrical apparatus, such as transformers, and more specifically to new and improved electrical bushings of the cast resin type.

2. Description of the Prior Art

Electrical insulating bushings of the type having an insulating body portion formed of a cast epoxy resin may be mounted on a casing enclosing electrical apparatus in many different ways, with the specific arrangement selected being determined by such factors as cost, application and intended environment of the apparatus. Regardless of the mounting arrangement selected, all of them must mechanically secure the bushings through an opening in the casing, while providing and maintaining a fluid tight seal between the casing and the bushing, or between the bushing conductor and the insulating body portion of the bushing. Further, an insulating fluid in the casing, such as oil, must not leak out of the apparatus through any of these locations. Since the end of the insulating bushing may be below the level of the insulating fluid, the interface between the conductor and the insulating body portion is particularly susceptible to fluid leaks.

In prior art cast resins bushings, it has been the practice to cast a metallic mounting member or flange into the resin body portion of the bushing. The bushing is then disposed in an opening in a metallic casing, and then the metallic flange is welded to the casing. This arrangement is excellent for obtaining a good mechanical structure and for insuring that there are no leaks between the mounting flange and the casing, but fluid leaks develop between the mounting flange and the cast body portion of the bushing, even when a gasket in the form of a resilient coating is applied to the mounting flange and cured or vulcanized, before it is embedded in the cast solid insulating material, because the welding heat damaged the bond between the coating and the mounting member, or between the coating and the cast solid insulation. Thus, it is desirable to be able to weld metallic mounting members or flanges to metallic casings, without permanently impairing the seal between the metallic mounting flange and the cast body portion of the bushing.

Prior art solved this problem by using a thermoplastic or elastomeric coating applied to the area of the flange which was embedded in the main cast body of the epoxy bushing. The reasons for this coating were two-fold. First, to act as a cushion to prevent the resin encapsulant from cracking due to mechanical stress set up during shrinkage of the resin onto the edge of the flange. Secondly, to act as a sealant to prevent the insulating fluids within the bushing assembly from leaking past the interface between the resin and the embedded flange. See as examples of prior art U.S. Pat. No. 3,504,106, issued to Keto, and U.S. Pat. No. 3,388,212, issued to Nichols.

Although these prior art devices provided an improvement over the previous prior art, problems were still encountered in that damage to the sealant by heat generated during welding still occurred and allowed leakage of fluid or loss of pressure in the bushing.

SUMMARY OF THE INVENTION

The present invention discloses a structure wherein a rigid metallic mounting member, or flange, is embedded into an epoxy or other resinous body member and forms a leak-free and pressure-tight seal without the need for a thermoplastic or an elastomeric coating being applied to the embedded portion of the metallic mounting flange.

10 The basic flange construction of the prior art is retained, but instead of applying such an elastomeric or thermoplastic coating, a thin, less rigid, metallic member, substantially cylindrical in shape, is attached, by weld or other suitable means, to the embedded portion of the rigid metallic mounting member. This thin, less rigid, metallic member may be treated with an epoxy or other similar enamel or such treatment that will promote adhesion between it and the encapsulant resin material. The object of disposing such a thin, less rigid, metallic member in the cast insulating body member is to provide an alternative method of preventing leakage of fluid or loss of pressure of the bushing assembly.

25 An advantage of this invention is that it is possible to eliminate the need for any thermoplastic or elastomeric coating or sealant that was required by the prior art in order to obtain a leak-free and pressure-tight bushing. This invention also eliminates possible damage to the bushing by heat generated during welding. The thin metallic member is flexible enough so that it moves with the encapsulating resin as the resin shrinks during gellation, thus eliminating any possible high mechanical stress areas which could cause cracking or breakage

30 of the bond between the thin metallic member and the encapsulating resin. A further advantage is that, being a thin membrane, the thin metallic member conducts heat very rapidly into its surrounding media, thus reducing the possibility of breakage of the bond between 35 the thin metallic member and the encapsulant should excessive heat be applied during welding.

40 The total effect of utilization of the teachings of this invention would be to provide a pressure-tight and leak-free bushing assembly, without the use of elastomeric or thermoplastic resinous material being disposed on that portion of the metallic mounting member which is embedded in the cast resinous body member. The elimination of the need for such thermoplastic or elastomeric resin leads to a simplification of manufacture and reduction or elimination of manufacturing errors which result under the conventional sealing method.

BRIEF DESCRIPTION OF THE DRAWINGS

55 Further advantages and uses of the invention will become more apparent when considered in view of the following detailed description and drawings, in which:

FIG. 1 is an elevational view, partially in section, of 60 an electrical bushing constructed according to the teachings of this invention;

FIG. 2 is an elevational view, partially in section, of another embodiment of the invention;

FIG. 3 is an elevational view, partially in section, of 65 still another embodiment of the invention; and,

FIG. 4 is an elevational view, partially in section, of yet another embodiment of the invention.

DESCRIPTION OF THE PREFERRED EMBODIMENT

Throughout the description which follows like reference characters refer to like elements in all Figures of the drawing. Referring now to the drawings, and FIG. 1, in particular, there is shown an electrical bushing assembly 10, partially in section, constructed according to the first embodiment of the invention.

Specifically, bushing 10 includes an axially extending electrical conductor means 14, formed of a good electrical conductor such as aluminum or copper, a substantially cylindrical insulating body member 16 formed of a cast, rigid solid insulation material such as filled epoxy resin, a first rigid metallic mounting member or flange 18, and a second less rigid metallic member 12.

Body member 16 has first and second ends 17 and 19, respectively, and may be cast of any suitable resinous insulation material which has the following characteristics. It must be a good electrical insulator, weather resistant, crack resistant, rigid but not brittle. It must possess a high physical strength at ambient and elevated temperatures, and it must have a coefficient of thermal expansion which closely matches the coefficient of thermal expansion of the electrical conductor means 14. Body member 16 is preferably cast, instead of being molded, because of the superior strength of cast resinous insulation systems over molded systems. In general, the filled epoxy cast resin systems will provide the desired characteristic, with the filler being selected to match the coefficient of thermal expansion of the filled resin system to that of the electrical conductor means. A finely divided filler, such as quartz or silica flour, has been found to be excellent in matching the coefficient of thermal expansion of the filled epoxy resin system to copper. For 7200 volt applications where the encased end of a bushing assembly is disposed in oil, or other insulating dielectric fluid, fillers for providing arc and track resistance are usually not required. If the encased end is to be operated in air, finely divided alumina trihydrate ($\text{Al}_2\text{O}_3 \cdot 3\text{H}_2\text{O}$) may be added to obtain the desired arc and track resistance.

The conductor 14 may be solid, as illustrated, or a walled tube, having an external end 20 adapted for connection to an external electrical circuit, and an internal end 22, immersed in a dielectric fluid or vacuum 24. The internal end 22 is connected to electrical apparatus housed in casing 28.

The first rigid metallic mounting member 18 has a generally circuit shaped central opening 21 therein defined by its flange or curved edge 25. The first rigid metallic mounting member has a predetermined continuous portion thereof adjacent to the opening 21 therein embedded in the insulating body member 16.

The first rigid metallic mounting member 18 may be formed of any suitable material, such as steel, copper, or aluminum, and is adapted for welding about its periphery by means of its flange 23 to the flange 27 of the casing 28 of the associated electrical apparatus, as illustrated by the welding bead 30. The metallic mounting member 18 is provided from metal having a thickness of approximately 1/16 of an inch and is considered to be a relatively inflexible or rigid member.

The second metallic member 12, having less rigidity than the first metallic mounting member 18, is attached to the first metallic mounting member 18 adjacent to

the opening 21 in the first metallic mounting member 18, as illustrated by the weld bead 32. The second metallic member 12 is substantially cylindrical in shape, and is completely embedded in the insulating body member 16. The metallic member 12 extends from its attachment to the first rigid metallic mounting member 18 for a substantial distance, such direction being substantially parallel to the electrical conductor means 14. The second metallic member 12 is a thin metallic membrane from 0.002 to 0.010 inch in thickness. The metallic member 12, may be constructed from steel, copper, aluminum, or any other suitable metal. The thickness of the second metallic member 12 permits the second metallic member 12 to be of sufficient flexibility so as to move with the insulating body member 16 as it shrinks or contracts during fabrication. It is important that metallic member 12 have less rigidity than the first rigid metallic mounting member 18, so that the metallic member 12 might flex and move with the resin body member 16 when the body member 16 expands and contracts without damaging the joint between the metal members 12 and 18. The second metallic member 12 is thin enough so that as to readily conduct heat to its surrounding media. Disposed on the second metallic member is a resinous material 34, such resinous material being utilized to cast the body member 16 so as to facilitate a bond between the second metallic member 12 and the insulating body member 16.

The second metallic member 12 is so attached to the first rigid metallic mounting member 18 and so disposed within the insulating body member 16 so as to eliminate the need for any thermoplastic or elastomeric sealant to make the electrical bushing assembly 10 leak-free and pressure-tight. The purpose of the second metallic member 12 being so disposed within the insulating body member 16 is to necessitate a longer path for any fluid encased within bushing 10 which seeks to escape from bushing 10 by passing to the flange of the mounting member 18 and along the interface between the flange 18 and resin body member 16 to the outside of the bushing.

A release material 36 is disposed over a portion of the electrical conductor means 14 which permits the electrical conductor means 14 to move with respect to the insulating body member 16 over most of the length of the electrical conductor means 14 when the electrical conductor means 14 expands or contracts due to thermal cycling. The release material 36 is disposed on the fluid side of the bushing. A suitable release material is silicone grease.

FIG. 2 is an elevational view, partially in section, of another embodiment of this invention. In this view, electrical bushing 10 is shown as having its first rigid metallic mounting member 18 disposed at an inward and upward angle with respect to the electrical conductor means 14. The second metallic member 12 is disposed so as to extend from the attachment of second metallic member 12 with first rigid metallic mounting member 18 in a direction substantially parallel to the electrical conductor means 14.

FIG. 3 shows an elevational view, partially in section, of still another embodiment of the invention. In this view the electrical bushing assembly 10 is shown as having its first rigid metallic mounting member 18 disposed so as to form an inward and upward angle with the direction of said electrical means 14 and the second metallic member 12 is disposed so as to form an angle

inward and downward with the direction of the electrical conductor means 14.

FIG. 4 illustrates an elevational view, partially in section, of still another embodiment of the invention. In this figure, the electrical bushing assembly 10 is shown as having the second metallic member 12 attached to the first rigid metallic mounting member 18, with the second metallic member 12 extending in two directions from the attachment of the second metallic 12 with the first rigid metallic mounting member 18.

In summary, the advantages of having the second metallic member 12 attached to the first rigid metallic mounting member 18, all completely embedded within said insulating body member 16, is to eliminate the need for any thermoplastic or elastomeric sealant. In the prior art such sealant was necessary so as to render the electrical bushing assembly 10 leak-free and pressure-tight. Utilizing the teachings of this invention and the disposition of the second metallic member 12, the need for such thermoplastic or elastomeric material is eliminated. As a result, any manufacturing error which heretofore would have rendered the electrical bushing assembly 10 defective due to leakage of the insulating dielectric fluid is eliminated. The thinness of the second metallic member 12 permits a rapid conduction of any excess heat generated by welding the external flange 23 of the first rigid metallic mounting member 18 to the casing flange 27 of the electrical casing 28 into the surrounding media. Such rapid conduction of heat will prevent the breaking of any bonds formed between the second metallic member 12 and the insulating body member 16 due to the presence of the resin 34. Also, the second metallic member 12 is flexible enough so that it is able to move with the encapsulating resin of the insulating body member 16 as the insulating body member 16 shrinks during gellation of the insulating body member 16 thus eliminating any possible high mechanical stress areas which could cause cracking or breakage of the bond between the second metallic member 12 and the encapsulating resins of the insulating body member 16.

Since numerous changes may be made in the abovedescribed apparatus and different embodiments of the invention may be made without departing from the spirit thereof, it is intended that all matter contained in the foregoing description or shown in the accompanying drawings shall be interpreted as illustrative and not in a limiting sense.

I claim as my invention:

1. An electrical bushing assembly for mounting on a casing containing oil dielectric with a portion of said bushing assembly extending into said oil dielectric, said bushing assembly comprising:
  - an insulating body member formed of solid insulation,
  - electrical conductor means extending centrally and axially through said body member,
  - a release material disposed about a predetermined portion of said electrical conductor means adjacent said oil dielectric,
  - a first rigid metallic mounting member having an opening therein, said first rigid metallic mounting member having a predetermined continuous portion around its opening embedded in said insulating body member,

a second thin and flexible metallic foil member attached to said first rigid metallic mounting member continuously about said opening therein with a fluid-tight seal, said second thin and flexible metallic foil member surrounding in spaced relationship a predetermined portion of said electrical conductor means,

10 a resin material disposed about said second thin and flexible metallic foil member, said resin material bonding said thin and flexible metallic foil member to said solid body member with a fluid-tight seal, said second thin and flexible metallic foil member extending from said fluid-tight seal with said first rigid metallic mounting member and being completely embedded in said insulating body member.

2. The electrical bushing assembly of claim 1 wherein said second thin and flexible metallic foil member extends from said fluid-tight seal with said first rigid metallic mounting member in a direction substantially parallel to said conductor means.

20 3. The electrical bushing assembly of claim 1 wherein said second thin and flexible metallic foil member extends from said fluid-tight seal with said first rigid metallic mounting member in a direction substantially perpendicular to said first rigid metallic mounting member and substantially parallel to said conductor means.

25 4. The electrical bushing assembly of claim 1, wherein said second thin and flexible metallic foil member is substantially cylindrical in shape.

30 5. The electrical bushing assembly of claim 1 wherein said second thin and flexible metallic foil member is disposed so as to extend from said fluid-tight seal with said first rigid metallic mounting member in one direction.

35 6. The electrical bushing assembly of claim 1 wherein said second thin and flexible metallic foil member is disposed so as to extend from said fluid-tight seal with said first rigid metallic mounting member in one direction, said direction being substantially perpendicular to said first rigid metallic mounting member and substantially parallel to said conductor means.

40 7. The electrical bushing assembly of claim 1 wherein said second thin and flexible metallic foil member is disposed so as to extend from said fluid-tight seal with said first rigid metallic mounting member in two directions from its attachment to said first rigid metallic mounting member.

45 8. The electrical bushing assembly of claim 1 wherein said second thin and flexible metallic foil member is disposed so as to extend from said fluid-tight seal with said first rigid metallic mounting member in two directions from its attachment to said first rigid metallic mounting member, said directions being substantially perpendicular to said first rigid metallic mounting member and substantially parallel to said conductor means.

50 9. The electrical bushing assembly of claim 1, wherein said first rigid metallic mounting member is fabricated of a material approximately 1/16 of an inch thick.

55 10. The electrical bushing assembly of claim 9, wherein said second thin and flexible metallic foil member is fabricated of a material having a thickness within the limits of 0.002 to 0.010 of an inch.
